ISAAC HIRSOHN, OF NEW YORK, N. Y.

COVERING RECEPTACLES.

1,036,237.

Specification of Letters Patent. Patented Aug. 20, 1912.

Application filed January 27, 1911. Serial No. 605,067.

To all whom it may concern:

Be it known that I, ISAAC HIRSOHN, a citizen of the United States of America, residing in the city, county, and State of New York, have invented certain new and useful Improvements in the Art of Covering Receptacles, which embody several novel and useful features.

My invention relates more particularly to that branch of the art wherein a sectional hinged cover is used.

Among the novel features embodied in my invention, are included a common pivotal bearing, upon which are pivotally mounted both the sectional hinged sectional cover and a bail, or handle, for lifting and emptying, or transporting the receptacle; this pivotal bearing is let through openings in projecting ears, fixed on the body of the receptacle, or on lugs affixed thereto, and is preferably removably mounted in any known manner. I also provide means for the automatic raising and lowering of the respective sections of the cover, as desired, by the depression of the bail, or handle, from its normal upright, or vertical position, in either direction, and its return to its normal position. I effect this, and at the same time provide an economical and commercially practical construction, by forming at each end of the bail, or handle, a spiral loop adapted to receive the pivotal support and hinge thereon, with an extension, or lateral arm projecting from the inner end of each loop, but in opposite directions, at right angles to the plane of the bail or handle. The sections of the cover projects sufficiently beyond the body of the receptacle so that one of these arms when the bail is normally upright, extends under each section of the cover, and the arms are respectively elevated by the bail, as it is depressed in opposite directions, carrying with them the over-lying sectional covers, and thus raising them.

For some purposes it is desirable that a section of a sectional cover may remain open when raised, and if required, lay over flat on the opposite section, until restored by operating the bail, while in other cases, it is required that the cover shall automatically return to its closed position, when opened, and shall maintain a close joint. I effect the desired results by providing a compression spring of any suitable pattern which is carried or maintained in place, by the pivotal bearing which carries the bail, or

handle, and sectional cover; the respective ends of the compression spring bear upon the upper surfaces of the opposite sections of the cover, and thus operatively depress either section, when open, as the bail is returned from a depressed to an upright position and such extremities of the spring, bear upon the cover when in place, thus maintaining a tight joint.

The common pivotal bearing referred to, is provided with threaded ends carrying wing nuts which not only facilitate the assembling of the parts and permit of the removal of the pivotal bearing and cover, at will, dispensing with the use of any tools, but such wing-nuts also possess the additional capacity of operatively controlling the compression spring and neutralizing the overcoming, as desired, the pressure of the spring, upon a section of the cover by simply turning up one of the wing nuts, thus increasing the frictional resistance of the contact between it and the hinged joint of the bail, or handle, upon which it bears. By a turn of the wing-nut, a section of the cover may be locked in an open position, and be released by a reverse turn. I do not limit my invention, however, to a removable pivotal bearing, as it is novel to mount, in any manner both the bail and sectional cover on a common pivotal support, while preferably removable, yet it may be permanently mounted on its bearings, by any construction known to the art for maintaining it, permanently in place, and any such construction is included in my invention.

Having thus generally described some of the novel features of my invention, I further and more particularly describe and specify the same by reference to the annexed drawings, which are illustrative sketches, as follows:

In the drawings, like letters and ordinals indicate similar parts.

Figures 1 and 2, are perspective views of a receptacle such as heretofore described, which is illustrated as applied to an ordinary pail, or bucket, and Figs. 3, 4, 5 and 6 are details showing and indicating, more particularly, the construction of the bail, or handle, and the method of mounting the same upon its pivotal support.

Referring to Fig. 1, A denotes the body of the receptacle; a. a., the cover; b., the bail, or handle; b¹ the spiral formed on the bail b.; and b² the angular extension formed

on said spiral, which is indicated on Fig. 1, and both indicated and shown on Fig. 2; *a. a.*, are the projecting ends, which are threaded, of the pivotal support, which is a 5 rod of any suitable material and diameter, upon which are journaled sections *a. a.* of the cover, and the outer ends of which rod are let through the openings *d¹ d¹* in the brackets *d. d.* and through the spirals *b¹ b¹* 10 formed on the bail *b*. This rod is removably maintained in place by the wing-nuts *e. e.*, between which, and the spiral *b¹* are preferably inserted a couple of washers. The wing-nuts *e. e.*, also serve as friction 15 clutches, when turned up, so that the bail, or handle working stiffly, does not yield to the pressure of the compression spring *f.*, and the cover may be thus locked in an open position, and released by a reverse turn of 20 the wing-nut, at will. The brackets *d. d.*, are shown in detail drawings Fig. 6, as riveted upon the body of the receptacle *A.* with ears projecting upward, sufficiently to permit of the openings *d¹ d¹* therein, to clear 25 the rim. The compression spring *f.* comprising a spiral carried by the pivotal rod *c.*, with projecting arms *f¹ f¹* bearing upon the upper surface of the cover sections *a. a.*, is located, as shown in the different figures of 30 the drawings.

Fig. 1 shows the cover sections *a. a.*, closed and the bail *b*, in its normal upright position, with the angular extension *b² b²* dotted in and indicated as bearing upon the 35 said respective cover sections *a. a.*, while Fig. 2, shows the bail depressed and left flat upon one of the covers *a.*, and the other cover *a.*, raised to an upright position and maintained therein by the angular extension 40 *b²* of the bail *b*.

The detail drawings Figs. 3, 4, and 5, illustrate the construction of the spiral *b¹* and angular extension *b²*.

Both the receptacle and its component 45 parts may be constructed of any suitable material and of such relative size as may be most convenient, having in view, the use for which such receptacle is to be adapted. As is obvious, to those skilled in the art, the 50 construction is especially adapted to the assembling, placement, and re-placement of the covers and bail, without either waste of time, or the requirement of any skill on the part of the operator, the construction 55 being particularly adapted for the separate packing of the bodies of the receptacle, which may be nested, and of the removable parts which may be packed, compactly, thus permitting economical transportation. In 60 the assembling of the removable parts for shipment, the pivotal rod *c.*, is first run through the alternate sections of the journals formed, in any usual manner, on the cover sections *a. a.*, to receive the same; it 65 is also carried through the spiral of the

spring *f.*; the wing nuts *e. e.*, are then mounted thereon. The retail dealer has only to withdraw the wing nuts, and pass one end of the rod through one of the openings *d¹* in one of the brackets *d. d.*, mount one spiral 70 of the bail *b¹* thereon, and then to retract the other end of the rod sufficiently so that the same may be brought into line with the opening *d¹* of the remaining bracket *d.*, and pass it through the opening, and the remaining spiral of the bail *b¹*, when the two wing nuts with the intervening washers, are reset upon the ends of the rod, and the former screwed into place.

When the parts are assembled, as described, the automatic action of the bail in opening and closing the respective sections of the cover by the mere act of depressing the bail in opposite directions, is obvious, and while such action is not novel, in the art, 80 yet the procurement of such automatic action by the simple and economical arrangement of parts, as here shown and described, is entirely novel, and I claim constitutes the first practical and economical application 85 thereof to render the same commercially operative.

Having thus specified and described the same, I claim as novel, and my invention:

1. In a covered receptacle, provided with 95 a hinged bail or handle, in combination, a hinged sectional cover, a common pivotal bearing having hinged thereon, such bail, or handle, and the sectional cover, and supports on the body of the receptacle for such 100 pivotal bearing.

2. In a covered receptacle, provided with a hinged bail or handle, in combination, a hinged sectional cover, a removable, pivotal bearing, having hinged thereon, such bail 105 or handle, and the sectional cover, and supports on the body of the receptacle, for such pivotal bearing.

3. In a receptacle, provided with a hinged sectional cover, in combination, a pivotal 110 bearing, a bail or handle, having a spiral loop formed on each end thereof, and hinged by such spiral loops on such pivotal bearing, on which is also hinged such sectional cover, and supports on the body of the receptacle for such 115 pivotal bearing.

4. In a receptacle, provided with a hinged sectional cover, in combination, a hinged bail or handle, having angular arms so formed at each extremity thereof, that the same project laterally in opposite directions, below the sectional covers when the bail is upright, a pivotal bearing on which such sectional covers and bail are hinged, and supports on the body of the receptacle for such 120 pivotal bearing.

5. In a receptacle, provided with a hinged sectional cover, in combination, a bail or handle, having a spiral loop formed on each 125 end thereof, with angular arms extending 130

therefrom, so formed that the same project laterally, in opposite directions, under the sectional cover, a pivotal bearing on which are hinged such bail or handle, and also 5 such sectional cover, and supports on the body of the receptacle for such pivotal bearing.

6. In a receptacle provided with a hinged sectional cover, in combination, a bail or 10 handle, having a spiral loop formed on each end thereof, with angular arms extending therefrom, so formed that the same project laterally in opposite directions, under the sectional cover, a removable bearing on 15 which is hinged, by such loops, such bail or handle, with such sectional cover, also hinged thereon, and supports on the body of the receptacle for such pivotal bearing.

7. In a receptacle provided with a hinged 20 sectional cover, in combination, a hinged bail or handle, having angular arms, so formed at each extremity thereof, that the same project laterally in opposite directions, under such sectional cover, a pivotal bearing, on which such sectional cover and bail are hinged, also carrying a compression 25 spring, whose extremities bear upon the respective cover sections, and adapted to alternately depress the same when raised, 30 as the bail is returned to a vertical position, and supports on the body of the receptacle for such pivotal bearing.

8. In a receptacle provided with a hinged 35 sectional cover, in combination, a hinged bail or handle, having a spiral loop near each end thereof, with angular arms projecting in opposite directions, laterally therefrom, under the sectional cover, a pivotal bearing on which is hinged, by such loops, 40 such bail or handle, and on which is also hinged such sectional cover, and supports on the body of the receptacle for such pivotal bearing.

9. In a receptacle, provided with a hinged 45 bail or handle, and a hinged sectional cover, in combination, a common pivotal bearing carrying such bail or handle and sectional cover, and supported on the body of the receptacle and means for automatically raising 50 either of the cover sections by depressing the bail from a vertical position, in an opposite direction.

10. In a receptacle provided with a hinged bail or handle, and a hinged sectional 55 cover, in combination, a common pivotal bearing, supported on the body of the receptacle, carrying such bail and cover, and means for automatically raising and lowering either section of the cover by depressing

the bail in an opposite direction and returning it to a vertical position.

11. In a receptacle provided with a hinged bail, or handle, and a sectional hinged cover, carried by a common pivotal bearing, supported on the body of the receptacle, in 65 combination, lateral lifting arms extended from the bail under the sectional cover in opposite directions, and adapted to raise either section of said cover when the bail is depressed in an opposite direction, and a 70 compression spring, bearing on said cover sections, and adapted to depress the same, as the bail is returned to a vertical position.

12. In a receptacle, provided with a hinged 75 sectional cover, and a hinged bail, or handle, having angular arms at each extremity thereof, projecting in opposite directions under the cover sections, in combination, a pivotal bearing on which such sectional cover and bail are hinged, ears on the body 80 of the receptacle supporting such pivotal bearing, a compression spring, carried by such pivotal bearing, and whose extremities respectively bear upon the upper surface of each of the cover sections, and means for adjustably overcoming the pressure of such spring upon either cover sections.

13. In a receptacle, provided with a hinged 85 sectional cover and a bail, or handle, having laterally projecting lifting arms, bearing on 90 the lower surface of each cover section, in combination, a common pivotal bearing with threaded ends, supported on the body of the receptacle, on which are hinged such bail and cover, a compression spring with its respective ends bearing upon the upper surface of such cover sections, and carried by such pivotal bearing, and wing-nuts on the threaded ends of such pivotal bearing, adapted to adjustably control the pressure 100 of such compression spring.

14. In a receptacle provided with a hinged 105 sectional cover, having the edges extended beyond the body of the receptacle near the bail, in combination, a bail having a spiral loop formed at each end thereof, with angular arms extending therefrom laterally, in opposite directions, under the sections of the cover and a pivotal bearing supported on the body of the receptacle, on which are 110 hinged the bail and cover.

In testimony whereof I affix my signature in the presence of two witnesses.

ISAAC HIRSOHN.
